Primary Examiner — Kimberly Barnes*Assistant Examiner* — Sarah A Nguyen(74) *Attorney, Agent, or Firm* — Hodgson Russ LLP(57) **CLAIM**

The ornamental design for a pool vacuum, as shown and described.

DESCRIPTION

FIG. 1 is a front-top-right perspective view of a pool vacuum, showing my new design;

FIG. 2 is a front-bottom-left perspective view thereof;

FIG. 3 is a front elevation view thereof;

FIG. 4 is a left side elevation view thereof;

FIG. 5 is a right side elevation view thereof;

FIG. 6 a top plan view thereof; and,

FIG. 7 is a bottom plan view thereof.

The broken lines in the figures illustrate portions of the pool vacuum that form no part of the claimed design.

1 Claim, 7 Drawing Sheets
